UNITED STATES PATENT OFFICE.

ELVIRA A. RUSSELL, OF MINNEAPOLIS, MINNESOTA.

IMPROVEMENT IN PRESSING-IRONS.

Specification forming part of Letters Patent No. **222,741**, dated December 16, 1879; application filed August 11, 1879.

To all whom it may concern:

Be it known that I, ELVIRA A. RUSSELL, of Minneapolis, in the county of Hennepin and State of Minnesota, have invented a new and Improved Pressing-Iron, of which the following is a specification.

The object of my invention is to provide a pressing-iron which is adapted to be placed over a lamp-burner like a chimney, and, while serving the same purpose, be heated by the flame of the lamp.

It consists in making the iron of the general form of a conical lamp-chimney, having one of its exterior sides flattened to form an ironing-surface, an extension at the smaller end on the flattened side to serve as a point for the iron, and at the large end a round portion to fit over the burner and hold the iron on the lamp-top.

In the accompanying drawings, Figure 1 is a sectional side elevation of my improved pressing-iron. Fig. 2 is a front-end elevation of the same; and Fig. 3 a side elevation of the improvement placed over a lamp-top.

Similar letters of reference indicate corresponding parts.

Referring to the drawings, A is the improved iron, of a general conoidal form, like a lamp-chimney, hollow inside, but having one side, B, flattened to form a smooth broad ironing-surface. This flattened side is extended slightly beyond the rounded sides at the smaller end, and formed into a V-shaped point, a, with inwardly-beveled extensions b b, which serve the purpose of the point of the ordinary iron—viz., to prevent the material from catching in the end of the iron, and to enable the ironing to be extended under tucks and in gathers or other similar places where a blunt end could not reach.

The large end or base of the cone below the end c of the flat surface B is rounded, forming a circular extension, C, to fit over the burner and hold the iron on the lamp-top.

On the convex side of the iron, opposite the flat surface, is fixed the handle D.

The manner of using the invention is as follows: In Fig. 3 is shown in dotted lines a lamp-top, E. Now, when the iron is to be heated it is turned to a vertical position with the large end down, and the extension C is placed over the burner and allowed to rest on the lamp-top like an ordinary chimney, as shown in Fig. 3. Thus arranged it serves the ordinary purpose of a chimney in giving a strong draft to the flame, and at the same time it is heated by the flame, and when it has reached the proper state can be removed and used as a pressing-iron.

This invention furnishes an excellent substitute for the furnaces now used for heating these irons in working-rooms. It is neater, does not give forth so much heat, and when the iron is removed this can be reduced so as to be not perceptible, is much more convenient in every way, and, lastly, is very economical, as the fuel used is in the most available form—viz., that of oil, and there is not the same waste as in the fuels used in furnaces.

I do not confine myself to the use of any particular form of burner or any particular devices for holding the iron on the lamp-top, as these may be varied to suit the wishes of those using the iron.

Having thus described my invention, I claim as new and desire to secure by Letters Patent—

As a new article of manufacture, a lamp-chimney pressing-iron having the hollow open-ended body A, with the V-shaped point a and inwardly-beveled extensions b b, as shown and described.

ELVIRA ACHMET RUSSELL.
